UNITED STATES PATENT OFFICE.

JOSEPH MADER, OF ALBANY, NEW YORK.

FLAG-RAISING DEVICE.

1,321,837.

Specification of Letters Patent. Patented Nov. 18, 1919.

Application filed July 30, 1919. Serial No. 314,297.

To all whom it may concern:

Be it known that I, JOSEPH MADER, a citizen of the United States, residing at #458 First street, in the city of Albany, county 5 of Albany, and State of New York, have invented a new and useful Flag-Raising Device, of which the following is a specification.

This invention relates to a flag raising device, and it is an object of the invention to provide a novel and improved device of this general character whereby a flag or the like may be readily and conveniently raised or lowered either manually or mechanically.

15 It is also an object of the invention to provide a novel and improved device of this general character including means whereby the flag or the like when lowered, can be conveniently protected against the 20 elements and without the necessity of entirely disengaging the flag or the like from the flexible member or cable with which it coacts.

The invention consists in the details of 25 construction and in the combination and arrangement of the several parts of my improved flag raising device whereby certain important advantages are attained and the device rendered simpler, less expensive and 30 otherwise more convenient and advantageous for use, as will be hereinafter more fully set forth.

The novel features of my invention will hereinafter be definitely claimed.

35 In order that my invention may be the better understood, I will now proceed to describe the same with reference to the accompanying drawings, wherein:

Figure 1 is a view in elevation illustrating 40 a flag raising device constructed in accordance with the embodiment of my invention, and in applied position certain of the parts being indicated by dotted lines.

Fig. 2 is a fragmentary view in elevation 45 illustrating in detail the operating mechanism as herein embodied, and,

Fig. 3 is a fragmentary view in elevation showing the flag part inserted within the 50 protecting tube or housing forming part of the present invention.

As disclosed in the accompanying drawings 55 11 denotes the superstructure of a building, and which has mounted thereon a tubular flag staff F. The staff F, as indicated in Fig. 1, has its lower portion extending within the building through the top thereof,

so that access may be had thereto without the necessity of going on the roof of the building.

3 denotes an endless flexible member, preferably a cable, which passes around the pulleys 6, rotatively supported by the opposite end portions of the flag staff F and one of the stretches of said endless member passes through the staff F, while the second 65 stretch is arranged exteriorly thereof.

2 denotes a flag or the like secured, as at 1, to the outer stretch of the flexible member 3, and the adjacent corner portion of the flag 2 is provided with a snap 12 or the 70 like whereby said last named corner portion can be detachably engaged with the flexible member 3.

Positioned adjacent to the lower portion of the flag staff F is a vertically disposed 75 tube or housing 13, having its upper end open and adapted to be closed by the door 5, hinged or otherwise secured thereto. The outer stretch of the member 3 passes through the tube or housing 13, so that when the 80 flag 2 is lowered, the same can be inclosed within said tube or housing 13 to protect the same effectually against the elements, and particularly when the door 5 is in closed position.

85 In order that the flag may be properly folded or Shirred to cause its insertion within the tube or housing 13, the snap 12 or the like is disengaged from the outer stretch of the member 3 so that the flag 2 will only 90 be engaged with the member 3 at 1.

The lower pulley 6 is mounted upon a shaft 10, having one end portion extended exteriorly of the flag staff F, and provided with a crank 7, whereby the pulley 6 may 95 be manually rotated, in order to either raise or lower the flag 2. The shaft 10 is also operatively engaged, as at 9, with the driving shaft 14 of a motor 8, preferably electric, so that the flag may be mechanically 100 raised or lowered.

Although not shown, it is to be understood that the operating circuit for the motor 8 is to be under control of a reversing switch of any desired type.

105 Interposed in the flexible member 3 is a turn buckle 4, operating to compensate for any slack which may occur in the member 3. The turn buckle 4 is so positioned as to operate as a stop to prevent the flag 2 from 110 being pulled around either of the pulleys 6, and which action is accomplished by con-

tact of the turn buckle with either of such pulleys.

From the foregoing description, it is thought to be obvious that a flag raising device constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein-after claimed.

I claim:

1. A flag raising device comprising a pair of vertically spaced pulleys, a flexible endless member passing around said pulleys, means for rotating one of said pulleys for imparting movement to the endless member, a flag secured to the endless member, and means carried by the endless member 25 and coacting with the pulleys for limiting the movement of the endless member in either direction, said last named means operating to take up slack in the endless member.
2. A flag raising device comprising a tubular staff, pulleys supported by the opposite end portions of the staff, an endless flexible member disposed around the pulleys, a stretch of said member being disposed 35 through the staff, and the second stretch

being arranged exteriorly thereof, a flag secured to the exterior stretch of the endless member, means for rotating one of the pulleys to either raise or lower the flag, and a housing positioned adjacent the lower portion of the staff and having its upper end open, said housing receiving the flag when in its lowermost position. 40

3. A flag raising device comprising a tubular staff, pulleys supported by the opposite end portions of the staff, an endless flexible member disposed around the pulleys, a stretch of said member being disposed through the staff, and the second stretch being arranged exteriorly thereof, a flag secured to the exterior stretch of the endless member, means for rotating one of the pulleys to either raise or lower the flag, a housing positioned adjacent the lower portion of the staff and having its upper end open, 45 50 said housing receiving the flag when in its lowermost position, and a means for closing said open end of the housing.

4. A flag raising device comprising a pair of vertically spaced guides, a flexible endless member passing around said guides, a flag secured to one of the stretches of the endless member, a housing positioned adjacent the lower portion of the endless member and having its upper end open, a stretch 60 65 of the endless member passing through the housing, said housing receiving the flag when in its lowermost position.

JOSEPH MADER.
